UNITED STATES PATENT OFFICE.

HERMAN GEORGE BENDIX AND HERMANN FORTH, OF BROOKLYN, NEW YORK,
ASSIGNORS TO MARK CANGAN, OF BROOKLYN, NEW YORK,
SHOE-HEEL-BREAST BUFFER AND PAPER-FORMER.

1,326,836.

Specification of Letters Patent.

Patented Dec. 30, 1919.

Application filed December 3, 1918. Serial No. 265,174.

To all whom it may concern:

Be it known that we, HERMAN GEORGE BENDIX and HERMANN FORTH, both citizens of the United States, and residents of the city of New York, borough of Brooklyn, in the county of Kings and State of New York, have invented a new and Improved Shoe-Heel-Breast Buffer and Paper-Former, of which the following is a full, clear, and

exact description.

This invention relates to shoe heel breast buffers and especially to buffers adapted for use in connection with Louis X type in which the heel breast is formed with a graceful forward upward turn where it merges into the instep and also is provided with a vertical cylindrical curve at the bottom.

More definitely stated, among the objects of our invention is to provide a buffer adapted for exceedingly high speed operation and having an abrasive surface formed of a minimum amount of carborundum per, or its equivalent, whereby the element of economy of material is observed.

A further object of the invention is to provide a means for shaping the abrading element and applying it to the buffer body, whereby a substantially perfect cylindrical or other symmetrical curved surface is obtained.

A further object is to facilitate the application of the abrading surface to the buffer body.

Another object of the invention is to construct a buffer, the main portion of the body, of which is relatively rigid, but having an end or point which is relatively flexible and whereby a more satisfactory operation of the buffer may be realized.

A still further object of the invention is to provide a buffer adapted for high speed rotation and having locking means to removably hold the abrading surface thereon in such a manner as not to materially dis-

50 view the invention consists in the arrangement and combination of parts hereinafter described and claimed, and while the invention is not restricted to the exact details of construction disclosed or suggested herein,

still for the purpose of illustrating a practical embodiment thereof reference is had to the accompanying drawings, in which like reference characters designate the same parts in the several views and in which—

Figure 1 is a perspective view of a rectangular piece of abrasive paper or the like prior to its formation into cylindrical form for application to the buffer body.

Fig. 2 is a perspective view indicating our improved former and one of the abrading sleeves thereon.

Fig. 3 is a perspective view of said sleeve separated from the former or buffer body.

Fig. 4 is a plan view partially in section indicating the manner of transferring the sleeve from the former to the buffer body.

Fig. 5 is a vertical longitudinal section of the buffer complete on a plane corresponding to the line 5—5 of Fig. 7.

Fig. 6 is a vertical transverse sectional view indicating the relation of the locking core at the time the sleeve is applied to the buffer body.

Fig. 7 is a similar view on the line 7—7 of Fig. 5 showing the locking action of the core.

Fig. 8 is a side elevation of the core detached and indicating the means for counter-balancing the same.

Referring now more particularly to the drawings we indicate at 10 a rectangular

piece of abrasive material such as fine sand paper, carborundum paper, or the like, cut of which is relatively rigid, but having an end or point which is relatively flexible and found in practice to be preferably substantially square. This member will be referred to for convenience hereinafter as the sleeve.

These sleeve blanks being cut or formed of uniform size and shape, their manipulation in forming and applying them to the buffer bodies may be performed expeditiously and reliably.

11 indicates a former consisting of a smooth cylindrical piece of material such as wood and having formed longitudinally therein a slot or kerf 12 extending outward

radially from approximately its center. One side wall of the kerf 12 is connected with the cylindrical outer surface along a relatively sharp shoulder 13 while the opposite edge portion 14 is reduced materially

- 22
- in radius as indicated in Fig. 2^a. The reduced side wall portion 14 of the former 5 may extend only a portion of the distance along the device, but extends from one end thereof toward the middle. The former is long enough for easy manipulation, keeping in mind that the buffer body ordinarily is retained fixed to the machine and hence is in rigid position when idle.
- 10 Our improved buffer includes a metallic shank 15 having a stem 16 threaded for rigid engagement with the machine spindle, not shown, but from which it will be understood to be given a high speed of rotation. The 15 shank has a hollow threaded center 17 and a longitudinally extending hollow cylindrical quill 18 having a slot along one side at 19 which extends from the outer end of the quill down almost to the shank 15. The 20 shank and quill, having a cylindrical surface 20, common to both of them are fitted with a flexible fibrous body 21 of good quality of felt, or its equivalent, the same being gripped at one end around the shank by 25 means of a collar 22 having any suitable fastening means such as set screws 23 extending therethrough radially into the felt body. This flexible body has a length such that it extends beyond the outer end of the quill 30 18 as indicated at 21' in Fig. 5, and has along one side a longitudinal slot 24 extending all the way from its open end to the inner end of the slot 19. The length of the slot 24 is substantially equal to that of the 35 abrasive sleeve.
- The remaining portion of the buffer body consists of a locking member 25 formed from a cylindrical piece of metal having a screw threaded central shank 26 whereby it 40 is rotatably fitted into the socket 17. One side, however, of the cylindrical body is reduced forming a spiral cam as indicated at 27, (Figs. 6 and 7), said cam extending circumferentially from a longitudinal radial 45 groove 28. The end of the locking body is provided with a tool slot 29 for rotation thereof. On the side or face of the body 25 opposite the groove 28 and the cam surface 27 the material is removed as shown at 30 by 50 any suitable means so as to render the locking member substantially balanced with respect to the axis of rotation, and whereby the tendency to cause vibration of the buffer when rotated at high speed is practically 55 eliminated.
- Having thus set forth the principal features of our construction, the manner of use thereof will be readily understood as follows: Considering the buffer body fixed to 60 the machine and held steady in position and with the core 25 turned to the position indicated in Fig. 6 with its groove 28 registering with the slots 19 and 24 it will be in position to receive the sleeve 10. We then take the 65 former 11 in hand and project one edge of a sleeve blank 10 directly into the kerf 12. While holding the blank in this position the main portion thereof will be broken or bent directly around the sharp edge 13 thereof forming a tongue or flange 10^a. This tongue 70 will be, therefore, of a uniform width substantially equal to the depth of the kerf. We then remove the sleeve from the kerf and apply the opposite side edge of the kerf and form the second flange 10^b in precisely the 75 same manner. With this second flange 10^b left in the kerf and the sleeve held upon the cylindrical surface of the former, the first formed flange 10^a will then be brought around into the kerf as indicated in Figs. 2 80 and 3. The reduced edge 14 of the former enables the operator to readily slip this latter mentioned flange down into the kerf alongside of and parallel to the flange 10^b. These flanges having been formed over the same 85 relatively sharp edge 13 of the former must be of the same width and with the exercise of no more than ordinary care the operator is able to fit the sleeve upon the former so as to occupy the position of Fig. 2 with facility, thereby forming a substantially cylindrical abrading surface for the sleeve and moreover forming a sleeve having a minimum amount of waste, the only waste material being the relatively narrow flange portions 90 95 10^a and 10^b. The next step is for the operator while still holding the flanged portion of the sleeve in the kerf 12 is to slip the sleeve endwise from the former directly upon the buffer body, the flanges 10^a and 10^b slipping 100 into the aligned groove 28 and slots 19 and 24 as shown in Fig. 6. The cylindrical surface of the former is substantially the same as that of the flexible body 21. In this consideration the reduced shoulder portion 105 14 of the former is negligible because the rigidity of the sleeve material 10 is such that while the operator holds the sleeve with these flanges in the kerf 12 the shoulder portions of the sleeve will naturally be substantially in the same cylindrical curve. At any rate when the sleeve is slipped upon the felt body which has a true cylindrical surface the sleeve automatically and directly conforms 110 thereto, while the flanges thereof are held temporarily stationary by the operator's fingers. While the sleeve is thus held upon the felt body with the fingers of one hand the operator grasping a screw-driver or like tool with his other hand will project the tool 115 into the slot 29 and turn the locking core 25 to the position shown in Fig. 7 causing the cam surface 27 to grip or bind the free edge portions of the flanges 10^a or 10^b against the inner surface of the quill. This action 120 furthermore tends to tighten the cylindrical portion of the sleeve upon the outer surface of the felt body whereby it will be fixed in the best possible form for practical operation.
- 130

The device is now ready for operation. The sleeve is essentially cylindrical and co-axial with the buffer body or shank. Most 5 of the sleeve is rigidly supported by means of the rigid quill 18, subject, however, to the resiliency of the felt body 21 forming a cushion. The outer end, however, of the sleeve supported only by the extended end 21' of the felt body is more flexible, which fact 10 is especially appreciated by those familiar with the operation of such devices. With respect to the element of economy of material we wish to point out that not only is the material cut and manipulated in the most 15 economical manner as already set forth, but the entire construction including the extended flexible end 21' makes for the possibility of operating practically every portion of the cylindrical portion of the sleeve until it is 20 worn out.

We claim:

In a heel breast buffer, the combination of a rigid hollow cylindrical quill having a longitudinal slot extending from one end thereof, a cylindrical resilient body fitted 25 upon the quill and having a longitudinal slot extending from its outer end and registering with the aforesaid slot, said resilient body being longer than the quill and having its outer end directly unsupported thereby, an 30 abrasive sleeve so formed from a rectangular blank as to have a cylindrical body conforming to the outer surface of the resilient body and having also parallel edge members projecting inward through said slots, and means 35 within the quill serving to engage said edge members to lock them in position and holding the abrading sleeve in place.

HERMAN GEORGE BENDIX.
HERMANN FORTH.
